US00D413858S

United States Patent [19]

Murakami et al.

[11] Patent Number: Des. 413,858

[45] Date of Patent: ** Sep. 14, 1999

[54] RECHARGEABLE BATTERY

[75] Inventors: **Shigeru Murakami; Ryoichi Yamane**,
both of Tokyo; **Toshimitsu Masuko**,
Koriyama, all of Japan[73] Assignee: **Sony Corporation**, Tokyo, Japan

[**] Term: 14 Years

[21] Appl. No.: 29/088,687

[22] Filed: May 29, 1998

[51] LOC (6) Cl. 13-02

[52] U.S. Cl. D13/103

[58] Field of Search D13/103; 439/96-100,
